PLANER

Paul S. Jackson, Rockford, Ill., assignor to
 Jackson Hydraulic Machine Co., Inc., Rockford,
 Ill., a corporation of Illinois

Application November 13, 1943, Serial No. 510,092

21 Claims. (Cl. 90—49)

1

It is the general object of the invention to provide a new and improved planer of simple construction and efficient operation.

Another object of the invention is to provide a planer with new and improved frame elements such as the bed, table and columns, constructed largely from standard metal shapes, welded together.

Another object is to provide a planer embodying spaced columns and a cross rail therebetween, together with a plurality of tool supports on said columns and rail, and novel and simplified mechanism for actuating said parts and for controlling the actuation thereof.

Another object is to provide a planer having a plurality of tool supports with new and improved means for actuating the supports at feed and traverse rates, and control mechanism selectively operable to determine the operation of each tool support.

Another object is to provide a planer with new and improved mechanism for feeding and traversing one or more tool supports.

Other objects will become readily apparent from the following detailed description, taken in connection with the accompanying drawings wherein:

Fig. 1 is a front elevation of a planer embodying the invention.

Fig. 2 is a fragmentary side elevation (looking at the right-hand side of Fig. 1).

Fig. 3 is an enlarged fragmentary side elevation of the right-hand end of the cross rail, with parts broken away and in section on the line 3—3 of Fig. 4.

Fig. 4 is a fragmentary section along line 4—4 of Fig. 3.

Fig. 5 is a fragmentary section along the line 5—5 of Fig. 3.

Fig. 6 is a fragmentary plan view of the parts of Fig. 3, partly in section, along line 6—6 of Fig. 3.

Fig. 7 is a fragmentary vertical section along the line 7—7 of Fig. 3.

Fig. 8 is a fragmentary section along the line 8—8 of Fig. 3.

Fig. 9 is an enlarged fragmentary front elevation of the lower right-hand tool support in Fig. 1, partly in section along line 9—9 of Fig. 11.

Fig. 9a is a fragmentary section along line 9a—9a of Fig. 9.

Fig. 10 is a view, partly in section, along line 10—10 of Fig. 9.

Fig. 11 is a view, partly in section, along line 11—11 of Fig. 9.

2

Fig. 12 is a view, partly in section, along line 12—12 of Fig. 10.

Fig. 13 is an enlarged fragmentary vertical section approximately along line 13—13 of Fig. 2.

Fig. 14 is a section along line 14—14 of Fig. 13.

Fig. 15 is a horizontal section along line 15—15 of Fig. 14.

Fig. 16 is a plan section approximately along line 16—16 of Fig. 14.

Fig. 17 is a fragmentary section approximately along the line 17—17 of Fig. 16.

Fig. 18 is a fragmentary front elevational view of the feed-traverse mechanism with a cover plate removed.

Fig. 19 is a fragmentary section along the line 19—19 of Fig. 18.

Fig. 19a is a section along the line 19a—19a of Fig. 19.

Fig. 20 is a view along the line 20—20 of Fig. 18.

Fig. 21 is a vertical section through the right-hand cross rail tool head along line 21—21 of Fig. 1.

Fig. 22 is a fragmentary view, partly in section, along line 22—22 of Fig. 21.

Fig. 23 is a fragmentary vertical section through the left-hand cross rail tool head along line 23—23 of Fig. 1.

Fig. 24 is a fragmentary view, partly in section, along line 24—24 of Fig. 23.

While there is illustrated in the drawings and hereinafter described, a preferred form of the invention, it is contemplated that various modifications may be made by those skilled in the art without departing from the spirit and scope of the appended claims.

In the form illustrated, the invention comprises, generally, a bed 30, a table 31 reciprocably mounted on ways 32 thereon, columns 33 and 34 extending upwardly from opposite sides of a somewhat central portion of the bed, a crosshead 35 between the upper ends of the columns, a cross rail 36 slidable vertically on the columns, and tool supports 37, 38, 39 and 40 mounted on the columns and cross rail. The bed 30, table 31, columns 33 and 34 and other parts of the planer are preferably fabricated from standard metal shapes, i. e., I-beams, angles, plates, channels, etc., welded together, as more fully disclosed in my co-pending application Serial No. 512,154, filed November 29, 1943. The tool supports may

embody reversible tool holders with cutters 41 of the type disclosed and claimed in my co-pending application Serial No. 510,091, filed November 13, 1943.

55 The cross rail 36 may be adjusted vertically on

the columns 33 and 34 by means of vertical screws 42 and 43 which engage suitable nuts (not shown) in the opposite ends of the cross rail. The screws 42 and 43 are arranged to be actuated simultaneously at feed or traverse speeds by means of mechanism illustrated partly in Figs. 13 to 20, and hereinafter described in more detail. These screws may also be disengaged from the feed-traverse mechanism and then serve as stationary lead screws for actuating the tool supports 37 and 38, as hereinafter described. The means for actuating the tool supports 39 and 40 will be described first.

The tool supports 39 and 40 are slideable transversely of the planer table as viewed in Fig. 1 (simultaneously or independently) and at feed and traverse rates. Furthermore, the tool supports carry swivel bases 44 (Figs. 1 and 21) on which are mounted tool slides 45 which are movable diametrically of the swivel bases, simultaneously or independently, and at feed and traverse speeds. The means for actuating the tool supports and tool holders includes splined shafts 47 and 48 (for the support 40 and its slide 45, respectively) and splined shafts 46 and 49 (for the support 39 and its slide 45, respectively). These splined shafts are arranged to be driven at feed and traverse speeds by a feed-traverse mechanism designated generally 50 (Figs. 1, 2 and 13), a vertical splined shaft 51, and gearing designated generally 52 (Figs. 1 to 3).

The connections from the splined shaft 46 to the tool slide 45 on the support 39 are shown in Figs. 21 and 22. A gear 53 is splined to the shaft 46 and is confined in a bracket 159, carried on support 40, to move laterally with that support. A gear 151 meshes with gear 53 and is rotatably mounted on bracket 150, concentric with shaft 47. Gear 151 has an integral beveled gear portion 152 which meshes with a beveled gear 54 on a short shaft 55 which carries a second beveled gear 56. Gear 56 meshes with a gear 57 which is rotatably supported on an axis extending radially of the swivel base 44 and is splined internally at 58 onto a feed screw 59. The screw 59 is rotatably supported at its ends on the tool slide 45 in bearings 60 and 60', and engages a non-rotatable nut 61 supported on the swivel base 44. A hand wheel 62 is provided for adjusting the tool slide manually. Thus, the tool slide 45 on the support 40 may be actuated in a direction radially of its swivel base 44 by operation of the splined shaft 46.

For moving the support 40 laterally on the cross rail 36, the splined shaft 47 (Figs. 5, 21 and 22) carries a gear 153 splined thereon and confined between laterally spaced portions of a bracket 154 carried on the support 40. Gear 153 meshes with a gear 155 formed integral with a nut 156 which engages a feed screw 157 stationarily mounted on the cross rail 36. The gear-nut 155, 156 is also rotatably mounted on the bracket 154, as shown best in Fig. 5. Thus, by operating the splined shaft 47, the tool head 40 may be moved to the right or to the left from the position illustrated in Fig. 1, depending upon the direction of rotation of the shaft 47.

The tool support 39 (Figs. 1, 23 and 24) carries parts duplicating those on the support 40, as illustrated in Fig. 22. This support is arranged to be moved laterally on the cross rail by means of a nut 161 which is threaded on the stationary feed screw 157, and is rotatably supported in a bracket 159 carried on the support 39. The nut 161 is arranged to be rotated to move the support.

As shown, the nut is formed integrally with a gear 160 which meshes with a gear 158, splined on the shaft 48. The gear 158 is confined between opposed portions of the bracket 159 so as to move with the support 39. Thus, the connection between the shaft 48 and the feed screw 157 is similar to that shown in Fig. 5 for the tool support 40.

The tool slide 45 on the tool support 39 (Fig. 1) is arranged to be actuated by screw and nut mechanism similar to that shown in Fig. 21 on the tool support 40. The connections from the beveled gear 54 on the short shaft 55 are slightly different, because the axis of the shaft 55 for the tool support 39 is in the same horizontal plane as that for the tool support 40. Thus, as shown in Figs. 23 and 24, the beveled gear 54 meshes with a beveled gear 162, which is rotatably mounted in a bracket 163 carried on the support 39 in a position concentric with the shaft 47. A gear 164 is formed integrally with beveled gear 162, and meshes with an idler gear 165, rotatably mounted on the bracket 163 in a position concentric with the shaft 48. A third gear 166 meshes with gear 165, is rotatably mounted on the bracket 163, and is splined to the shaft 49. Thus, the shaft 49 is operable through an intervening gearing to actuate the tool slide 45 carried on the tool support 39.

It is to be noted that there are no disconnectable clutches or other devices intermediate the splined shafts 46, 47, 48 and 49, and the tool supports and slides which they are connected to actuate. Furthermore, as hereinafter set forth, the four parallel splined shafts in the cross rail all derive their power from the vertical splined shaft 51. A means for selectively connecting the horizontal splined shafts 46 to 49 to the vertical splined shaft 51 for simultaneous or independent actuation of the tool supports and slides is comprised in the gearing 52 (Figs. 1 to 4) which gearing will now be described.

As illustrated herein, the splined shafts of the cross rail are rotatably mounted in and extend through the ends 70 and 71 of the cross rail to terminate in squared ends as shown in Figs. 1 and 4. The shafts are parallel to each other but are arranged along the arc of a circle, as shown in Figs. 2 and 3. Pairs of pinions 72 are splined to the shafts and are shiftable to the right and left from the neutral positions shown in Figs. 4 and 6 to 8, so as to be engageable with either of large gears 73 and 74. These gears are rotatably supported on the cross rail and, as shown best in Fig. 7, carry beveled gears 75 and 76, fixed thereon, which mesh with a common pinion 77 which is rotatably supported on the cross rail and is splined to the shaft 51. Thus, when the shaft 51 is rotated, the large gears 73 and 74 rotate in opposite directions and provide for forward and return movements of the tool supports and slides when the pinions 72 are engaged with one or the other of the gears 73 and 74.

In order to shift the pinions 72, each is provided with an annular groove 78 in which a yoke 79 (Figs. 6 and 8) is engaged. The yokes are carried on horizontally slideable pins 80 (Figs. 3 and 6) which have rack teeth 81 thereon. Control handles 82, 83, 84 and 85 are swingably mounted on a common vertical pivot pin 86 and have segmental gear portions 87 meshing with the rack teeth. As viewed in Fig. 6, the control handle 82 may be swung to the left to engage the pinion 72 with gear 74, and to the right to engage the pinion with the gear 73. The control handles for the different tool supports and slides are in-

dependently operable so that the supports and slides may feed (or traverse) in like or opposite directions, or remain idle, depending upon the selections made by the operator of the machine.

The splined shaft 51 is arranged to be rotated at feed speeds, but in a single direction, in view of the reversing devices incorporated in the gearing 52. For convenience, the shaft 51 is arranged to be driven in forward and reverse directions at a traverse speed, by reversing the traverse motor hereinafter described. The actuation of shaft 51 at feed and traverse rates is accomplished by the feed-traverse mechanism 50 (Figs. 1, 2 and 13 to 20).

Referring now to Figs. 13 and 15, the feed-traverse mechanism includes a horizontal shaft 90 extending from the mechanism 50 (Fig. 1), through the bed 30 of the machine, through a casing 91 and into a casing 92. A beveled gear 93 on the left-hand end of the shaft meshes with a gear 94 on the lower end of a vertical splined shaft 95. As shown in Fig. 13, a beveled gear 96, splined and screwed onto shaft 99 adjacent the right-hand end thereof, meshes with a gear 97 on the lower end of splined shaft 51. Thus, the splined shafts 51 and 95 are driven simultaneously by the shaft 90, and at the same rate of speed (the gear sets 93, 94 and 96, 97 being of the same ratio) for a purpose hereinafter more fully described in connection with the tool supports 37 and 38.

The shaft 90 is arranged to be driven at a relatively high or traverse speed by means of a traverse gear 100 (Fig. 13), which is loose thereon, and a jaw type traverse clutch 101, 102 which is engageable to drive the shaft 90 from gear 100. The jaws of this clutch are herein shown formed on the gears 96 and 100. The gear 100 may be driven at a constant speed by an electric motor 302 (Figs. 1 and 18) by means of a pinion 302' on the motor shaft and a wide idler gear 302'' meshing with the pinion and with the traverse gear 100.

Shaft 90 is arranged to be given an intermittent and relatively slow feed movement by means including a jaw type feed clutch 103, 104 (Figs. 13, 15 and 19), the element 103 of which is splined to and slidable on the shaft 90, and is urged to the right (Fig. 13) by a coiled spring 105. The clutch element 104 is formed integrally with a spur gear 106 which is rotatable on the shaft 90 and held between a collar 107 and a hollow hub 108 formed on a cylinder 109. The gear 106 meshes with a pair of larger gears 110, 111 (Figs. 14 and 15) which, in turn, are mounted on shafts 112, 113, respectively, by means of overrunning clutch devices 126 and 127. Pinions 114, 115, fixed on said shafts, respectively, engage racks 116, 117 which are slidable vertically on opposite sides of the cylinder 109 in guideways 116', 117'. At their upper ends, the racks are secured to a crosshead 118 by means including screws 119. This crosshead is carried on a hollow piston rod 120 which has a piston 121 secured to its lower end and slidable in the cylinder 109. The stroke of the piston and its rod is adjustable and under the control of a vertically adjustable stop block 122 (Fig. 13) which is slidably supported in a hollow head 123 secured to a casing 124 which encloses the feed-traverse mechanism. The block 122 is screw-threaded and mounted on a screw 122', the upper end of which has a hand wheel 124. The screw 122' extends downwardly into the hollow piston rod 120. A screw device 125 is provided to lock the screw 123 in its adjusted position.

The means just described for giving the shaft

90 an intermittent feed movement includes the overrunning clutches 126 and 127 (Fig. 15) connecting the gears 110 and 111 to the shafts 112 and 113, respectively. These overrunning clutches 5 may be of a form well known in the art, adapted to transmit power in one direction of rotation and to overrun without transmitting power in the opposite direction. The clutches are arranged so that when the racks 116, 117 move upwardly 10 (Fig. 14), the clutch 126 functions to drive the shaft 112 while the clutch 127 overruns idly on the shaft 113. When the racks 116, 117 move downwardly, clutch 127 functions to drive the shaft 113 and clutch 126 overruns idly. Thus, 15 the shaft 90 is driven intermittently in a single direction of rotation, but alternately, by the gears 110 and 111.

To provide for fewer feed movements of the shaft 90 for each up and down movement of the piston 121, means is provided for disengaging the pinions 114 and 115 from their associated racks 116 and 117. As shown best in Figs. 15 to 20, the pinions 114 and 115 are provided with yoke grooves 130 which are engageable by yokes 131 carried on arms 132. These arms are secured to pivot pins 133 which carry operating handles 134 on their upper ends.

It is contemplated that the table of the machine will be reciprocated by fluid under pressure 30 operating on piston and cylinder devices, one for moving the table in a forward direction and the other for moving the table in a return direction, as disclosed in said copending application Serial No. 512,154, filed November 29, 1943. The upper end of the feed cylinder 109 is preferably connected continuously to a source of fluid under pressure which urges the piston 121 downwardly therein. At the end of the forward movement of the table, fluid under like pressure is admitted 35 to the lower end of the cylinder 109. Since the area of the lower end of piston 121 is approximately double the area of the upper end of the piston, the piston is thus moved upwardly by a differential action at the end of each forward stroke of the table. This pressure on the lower end of the piston is maintained during the return stroke, at the end of which it is removed, permitting the fluid under pressure on the upper end of the piston to return it downwardly. Thus, 40 the feed cylinder will be actuated at each end of the table movement. This arrangement is desirable when the planer is set up with reversible tool holders (as illustrated in Figs. 1 and 2) having forward and return stroke cutting tools 41.

If the machine is set up with tools arranged to 45 cut only when the table moves in a forward direction, the pinion 114 (or the pinion 115, as the case may be) can be disengaged from its actuating rack by means of the appropriate handle 134, so that the shaft 90 (assuming the feed clutch 103, 104 to be engaged) will be given a feed movement only at one end of the table movement, generally at the end of the return stroke thereof.

In the form illustrated herein, the cross rail feed screws 42 and 43 (Fig. 1) are also arranged to be driven from the traverse drive gear 100 (Fig. 13) for elevating and lowering the cross rail. As shown in Fig. 13, the left-hand end of gear 100 forms one element 137 of a jaw type clutch, the other element 138 of which is formed integrally with a beveled gear 139, rotatably supported in the casing 124 by bearings 140. Gear 139 meshes with a gear 141 splined on the lower end of the feed screw 43. The drive for the feed screw 42 includes a sleeve 142 which surrounds

a portion of the shaft 90, and at its right-hand end (Fig. 13) has a splined connection at 143 with the gear 139. The left-hand end of the sleeve 142 has a similar splined connection with a beveled gear 144 (Fig. 1) which meshes with a gear 145 fixed to the lower end of feed screw 42. With the clutch 137, 138 engaged, the cross rail may be raised and lowered by operating the traverse motor in forward and reverse directions.

The tool supports 37 and 38, with the exception of being left-hand and right-hand, are substantially the same in construction, so only the right-hand tool support 38 will be described.

As illustrated in Figs. 1 and 9 to 12, the support 38 is slidable on ways 170 on the column 34, and may be clamped in its adjusted position by tightening the gib screws. A nut 171 is rotatably mounted on the support 38 in a bracket 172 (Fig. 9a), and engages the feed screw 43. This nut has a pinion 173 thereon meshing with a pinion 174 fixed on a parallel, vertical shaft 175. A beveled pinion 176, integral with pinion 174, meshes with a beveled gear 177 on a horizontal shaft 178 which extends beyond the support to present a squared end 179 (to facilitate manual adjustment of the tool support).

For power actuation of the support 38, a pair of gears 180 is splined onto the shaft 178 and is shiftable thereon for engagement with either of gears 181 (Fig. 12) or 182. A yoke 183 engages the gears 180 and is carried on a horizontally slidable rod 184 which has rack teeth 185 thereon. A control handle 186 is pivotally mounted on a pin 187 and secured to a segmental gear 188 which meshes with the rack teeth 185. The gears 181 and 182 are arranged to be driven in opposite directions from the vertical splined shaft 51. Thus, as shown in Fig. 12, gear 181 is secured to a beveled gear 190, rotatably supported on a fixed shaft 191. The gear 182 is carried on a beveled gear 192 rotatably supported on a concentric, fixed shaft 193. A beveled gear 194, rotatably mounted on a bracket or casing 195 on the support 38, is slidably splined to the shaft 51 and meshes with the beveled gears 190 and 192.

As illustrated in Figs. 1 and 2, the tool support 38 is provided with a swivel base 44 and a tool slide 45, the same as the tool support 40 illustrated in detail in Fig. 21. The showing of the swivel base, tool slide, etc., has been omitted in Figs. 9 to 11 because they are duplicates of the corresponding parts illustrated in Fig. 21. Thus, in Fig. 10 there is indicated only the shaft 55 and attached beveled gear 54 of the gearing connections to the tool slide, the remainder of the connections being as shown in Fig. 21.

To actuate the tool slide 45 on the tool support 38, a horizontal shaft 200 is rotatably mounted on the tool support 38 (Figs. 9 to 11). At the left-hand end of the shaft 200, as shown in Figs. 9 and 10, there is a beveled gear 201, meshing with the gear 54. Adjacent the right-hand end of the shaft 200 is a pair of gears 202 splined to and shiftable on the shaft. These gears may be shifted into engagement with gear 181 or gear 182 for the purpose of driving the shaft 200 in one direction or the other. The gears 202 are arranged to be shifted by means of a yoke 203 carried on a horizontally slidable rod 204 on which rack teeth 205 are formed. A control handle 206 is pivoted on a horizontal pin 207 and carries a segmental gear 208 meshing with the rack teeth 205 to enable the desired shifting of the gears 202.

The tool slides may be operated manually by

the hand wheels 62 when the handles 82 and 84 are in their neutral positions as shown. When some of handles 82 to 85, 186 and 206 have been operated to engage the drive controlled thereby, the corresponding tool supports or slides will be fed or traversed in accordance with the position of the clutches in the feed-traverse mechanism 50. As shown in Fig. 13, the traverse gear 100 is de-clutched from the shaft 90 and from hollow shaft 142, and the feed clutch 103, 104 is engaged.

The traverse and feed clutches are controlled electrically in the form of the invention herein disclosed. As shown in Figs. 18 to 20, yoke 210 engages an annular groove 211 in the gear 100, and is operable by means including a link 212 which is connected to the yoke by a pin 213 and is also connected by a pin 214 to the upper end of a lever 215 which is supported intermediate its ends on one end of a shaft 216. This shaft is rotatably mounted in a bracket 217 which is secured to the casing 124 by screws 218 and is braced at its lower edge (Fig. 20) by a spacing tube 219 and a long bolt 220. The bracket has aligned cylindrical bores 221 and 222 (Fig. 19) which receive cylindrical guide rods 223 and 224, one on the yoke 210 and the other on a yoke 225 for the feed clutch part 103. The pin 214 on lever 215 carries a roller 226, and a pin 227 extending from the lower end of the lever carries a roller 228. An actuator 229 for the feed clutch is secured at one end to the feed clutch yoke 225 by a headed screw 230, and extends to the left therefrom (Figs. 18 and 19). At its left-hand end the actuator 229 has a transversely extending vertical rib 231 which serves as an abutment for the rollers 226 and 228, the parts assuming the positions shown in Figs. 18, 19 and 19a when the feed clutch is engaged by action of the spring 105.

A horizontally extending lever 232 is secured at right angles to the lever 215 by screws 233, and at its ends carries pins 234 and 235 which connect to the upper ends of links 236 and 237, the lower ends of which are connected to the armatures 238 and 239 of solenoids 240 and 241, respectively.

When the solenoid 240 is energized, the armature 238 thereof is pulled down and the levers 232 and 215 are rocked in a counter-clockwise direction from the position of Figs. 18 and 19a. Link 212 then acts to move the yoke 210 and gear 100 toward the left (Figs. 18 and 19), thereby engaging the cross rail elevating clutch 137, 138. The upper roller 226 on the lever 215 simultaneously forces the actuator 229 to the left by acting against the rib 231, and disengages the feed clutch 103, 104. When the solenoid 241 is energized, the armature 239 thereof is pulled down and levers 232 and 215 are rocked in a clockwise direction so the link 212 acts to pull the gear 100 to the right and engage the traverse clutch 101, 102. During this movement of the levers, the lower roller 228 acts against the rib 231, and also moves the actuator 229 to the left from the position shown in Figs. 18 and 19, and again disengaging the feed clutch 103, 104.

Thus, the feed clutch is normally engaged by the spring 105 when the traverse gear 100 is in its neutral position, as shown in the drawings, and when the traverse gear is shifted in one direction or the other from neutral, the feed clutch is disengaged by actuator 229.

Preferably, the solenoid 240 is controlled by means including push buttons 250 and 251 (Fig. 1) on a pendant station 252, conveniently located at the side of the machine. The push button 251

also controls switch means for operating the traverse motor 302 in a direction to raise the cross rail 36, and the button 252 controls switch means for reversing the traverse motor to lower the cross rail, the simultaneous energization of the solenoid 240 engaging the cross rail, elevating clutch 137, 138. Solenoid 241 (which, when energized, engages the traverse clutch 101, 102) is preferably controlled by push buttons 253 and 254 simultaneously with their control of the traverse motor. Button 253 also controls switch means for running the traverse motor in a forward direction, and button 254 controls switch means for operating the traverse motor in a return direction, for the tool heads. Button 255 is operable to stop a motor for operating the pumps for supplying fluid to the table and other actuating mechanisms, the starting of such motor being manually controlled.

With the preferred form of the invention as disclosed herein, it is contemplated that the tool slides 45 will be provided with reversible tool holders carrying oppositely positioned cutting tools 41 (Figs. 1, 2 and 21), one of which is effective to engage and cut the work when the table 31 moves in a forward direction, and the other of which is arranged to engage and cut the work when the table moves in a return direction. As illustrated in Fig. 21, the tool slide 45 has secured thereon a swivel base 260 which has formed integrally therewith a central, cylindrical hub 261 engaging in a bore 262 in the slide. The base 260 carries a plurality of bolt devices 263, the heads of which engage in a circular T-slot 264 in the slide 45, so that the base 260 may be turned through 360° of adjustment on the slide.

A tool holder 265 is pivotally mounted on a pair of laterally spaced brackets 266 on the base 260 by means of a pivot 267, and is movable from the position shown in Fig. 21 (wherein the left-hand tool 41 is in a cutting position) in a clockwise direction to place the right-hand cutting tool 41 in a cutting position for the return stroke of the table. The tool holder is arranged to be shifted between its two positions by means of a piston 268, operating in a cylinder 269, the piston being connected by means of a rod 270 to the upper end 271 of the tool holder 265. It is contemplated that the tool holder will be shifted at the end of each stroke of the table 31 by connecting the opposite ends of the cylinder 269 to the forward and reverse cylinders of the table, so that the right-hand end of the cylinder 269 will be connected to the supply of the actuating fluid for the table when the table moves in its forward direction, and the left-hand end of the cylinder 269 will be connected to the fluid supply when the table moves in its return direction.

As disclosed herein, the invention is embodied in a machine which provides for extremely convenient set-up and efficient operation. An operator standing adjacent the push button station 252 is within reach of the control handles 82, 83, etc., and by first moving the proper handle to the desired position he can then traverse the tool heads to their starting positions by manipulating the buttons on station 252. Similarly, the tool heads on the columns may be adjusted to their starting positions. The operating handles 134 for adjusting the feed mechanism, as well as the hand wheel 124 for adjusting the stroke of the feed mechanism, are all convenient to the operator in this same position. Similarly, the operator, by the use of the proper buttons 250 and 251, may raise and lower the cross rail 36.

Upon setting up the machine for cutting in either one or both directions of movement of the table 31, it is contemplated that the table will reciprocate continuously until the cutting operation is completed; the tool heads during such cutting operation being fed along their supports at the end of the forward and/or return movements of the table. Since the solenoids 240 and 241 are then de-energized, the feed clutch 103, 104 is engaged so as to effect the necessary feed movements of the supports.

By providing continuous mechanical connections intermediate the feed traverse mechanism 50 and the tool supports, subject only to operation 15 of the control handles 82, 83, etc., for selecting the tool supports to be operated and their direction of movement, an extremely simple structure is provided, all movements imparted to the tool support being determined in the feed traverse mechanism 50. The control handles 82, 83, etc., permit one or more of the tool supports to be adjusted or to be connected to feed during operation 20 of the machine. As disclosed herein, the feed traverse mechanism is also effective to raise 25 and lower the cross rail.

I claim as my invention:

1. In a planer, in combination, a reciprocating table, means for reciprocating said table, a tool support, a reversible tool holder on said support having forward and return cutting positions, and pressure fluid operated means for feeding said tool support and shifting the tool holder to its return cutting position at the end of the forward table movement, said pressure fluid operated 30 means being operable to feed said tool support and shift said tool holder to its forward cutting position at the end of said table movement in a return direction.

2. In a planer, in combination, a table, means for reciprocating said table, a tool support, means for feeding said tool support comprising a piston and cylinder device, a pair of racks reciprocable by said device, a feed shaft, gearing intermediate one of said racks and said feed shaft including 45 an overrunning clutch enabling said device to actuate the feed shaft when the piston moves in one direction in the cylinder and ineffective to actuate the feed shaft when the piston moves in the opposite direction, and gearing intermediate 50 the other rack and said feed shaft including an overrunning clutch effective to operate the feed shaft when the piston moves in the opposite direction and ineffective to actuate the feed shaft when the piston moves in said one direction.

3. A planer as defined in claim 2, having manual means selectively operable to engage and disengage the gearing between said racks and feed shaft.

4. A planer as defined in claim 2, having means for adjusting the stroke of said piston and cylinder device.

5. In a planer as defined in claim 2, said piston and cylinder device including a hollow piston rod, a fixed support disposed at one end of said device, a screw journaled in said support but held against axial movement therein and extending in telescopic relation with said hollow piston rod, and a stop nut carried by said screw in position to engage the end of the piston rod and adjustable by rotation to the screw for determining the stroke of the device and the feed movement imparted thereby to the feed shaft.

6. In a planer, in combination, a table, means for reciprocating said table, a tool support, means 70 for feeding said tool support comprising a pis-

11

ton and cylinder device, a feed shaft, gearing intermediate said device and said feed shaft including an overrunning clutch enabling said device to actuate the feed shaft when the piston moves in one direction in the cylinder and ineffective to actuate the feed shaft when the piston moves in the opposite direction, and gearing intermediate said device and said feed shaft including an overrunning clutch effective to operate the feed shaft when the piston moves in the opposite direction and ineffective to actuate the feed shaft when the piston moves in said one direction.

7. A planer as defined in claim 6 having means for adjusting the stroke of said piston and cylinder device.

8. In a planer as defined in claim 6, a fixed support disposed at one end of said piston and cylinder device, and a stop block having threaded engagement with said support and adjustable thereon toward and from the piston to arrest its movement in one direction.

9. In a planer, in combination, a table, means for reciprocating the table, a tool support, hydraulically operable means for feeding said tool support at each end of the table movement, and means adjustable at will for preventing operation of said feeding means at one end of the movement of the table when the table is reciprocated, while permitting operation of the feeding means at the other end of the table movement.

10. In a planer, in combination, a table, means for reciprocating said table, a tool support, and means for feeding said tool support comprising a piston and cylinder device, a pair of oppositely facing racks slidably mounted one at each side of the cylinder, a piston rod extending from one end of the cylinder, a cross head on said piston rod connecting said racks thereto for reciprocating them, a pair of pinions meshing with said racks respectively, a feed shaft, a gear fixed on said shaft, a pair of gears both meshing with said gear, an overrunning clutch connecting one of said pinions to one of said pair of gears enabling the piston to actuate the feed shaft when said piston moves in one direction, and a second overrunning clutch connecting the other pinion to the other gear of said pair enabling the piston to actuate the feed shaft further in the same direction of rotation when the piston makes its return stroke.

11. In a planer as defined in claim 10, one of said pinions being axially slidable for disengagement from its respective rack and means for so shifting said pinion at will.

12. In a planer, in combination, a cross rail, a tool support thereon, a tool slide on said support, a pair of splined shafts rotatably mounted on said cross rail, a feed-traverse mechanism, a vertical splined shaft extending from said feed-traverse mechanism and adjacent to said splined shafts on the cross rail, a pair of spur gears rotatably mounted on the cross rail adjacent said vertical shaft, a beveled pinion splined on said shaft and meshing with beveled gears on said spur gears to drive said spur gears in opposite directions, pinions slidably splined on said cross rail shafts, means for selectively engaging said pinions with one or the other of said spur gears, a non-rotatable feed screw on said cross rail parallel to the splined shafts thereon, a revolvable nut carried on said tool support engaging said feed screw, gearing intermediate one of said cross rail splined shafts and said nut, and means carried on said

12

tool support and driven by the other of said splined shafts for actuating said tool slide.

13. In a planer having a cross rail and tool supports thereon, a plurality of splined shafts rotatably mounted on said cross rail, means connecting said splined shafts to actuate said tool supports whenever the splined shafts are actuated, and means for actuating said splined shafts comprising a vertical shaft adjacent one end of the cross rail, power operated means for actuating said vertical shaft intermittently at feed rate and separate power operated means for actuating said vertical shaft at traverse speed, a pair of spur gears on said cross rail and driven in opposite directions from said vertical shaft, and pinions on said cross rail shafts selectively engageable with one or the other of said spur gears.

14. In a planer having a cross rail and tool supports thereon, a plurality of splined shafts rotatably mounted on said cross rail, means connecting said splined shafts to actuate said tool supports, and means for actuating said splined shafts comprising a vertical shaft adjacent one end of the cross rail, means for actuating said vertical shaft including a cylinder and piston device with a positive stop adjustable to limit the stroke of said device, a pair of spur gears on said cross rail and driven in opposite directions from said vertical shaft, and pinions on said cross rail shafts selectively engageable with one or the other of said spur gears.

15. In a planer having a movable tool support and a tool slide thereon, in combination, means for moving said support, a stationary feed screw, a nut rotatably carried on said support and engaging said screw, a pair of oppositely rotatable spur gears, means for driving said gears at feed and traverse rates, a first pinion connected to drive said nut and shiftable into and out of engagement with either of said spur gears selectively, gearing for actuating said tool slide including a second shiftable pinion selectively engageable and disengageable with said spur gears, and a control device for each of said shiftable pinions.

16. In a planer, in combination, a column, a tool support movably mounted thereon, a tool slide on said support, a feed screw on said column, a nut carried rotatably on said support and engaging said screw, a vertical splined shaft adjacent the column, means for driving said splined shaft at feed and traverse rates, a beveled pinion splined on said shaft and rotatably mounted on said support so as to be movable therewith on said column, a pair of oppositely positioned beveled gears engaging said pinion, spur gears carried on said beveled gears so as to be driven in opposite directions by said pinion, a first shiftable gear engageable alternately with said spur gears, means connecting said first shiftable gear to drive said nut, a second shiftable gear also engageable alternately with said spur gears, and means driven by said second shiftable gear for actuating said tool slide.

17. In a planer, in combination, a frame element, a tool support movably mounted thereon, a tool slide on said support, a feed screw in said frame element, a nut carried rotatably on said support and engaging said screw, a splined shaft adjacent the frame element, means for driving said splined shaft at feed and traverse rates, a beveled pinion splined on said shaft and rotatably mounted on said support so as to be movable therewith on said frame element, a pair of oppositely positioned beveled gears engaging said

pinion, spur gears carried on said beveled gears so as to be driven in opposite directions by said pinion, a first shiftable gear engageable alternately with said spur gears, means connecting said first shiftable gear to drive said nut, a second shiftable gear also engageable alternately with said spur gears, and means driven by said second shiftable gear for actuating said tool slide.

18. A planer having, in combination, a column, a cross rail, a plurality of tool supports on said column and cross rail, a splined shaft extending adjacent said column, means for actuating said shaft at feed and traverse rates, a feed screw in said column, a feed screw in said cross rail, a plurality of splined shafts on said cross rail, means on a cross rail tool support permanently connected to one of said splined shafts and said screw for actuating the support when the splined shaft is operated, a tool slide on said support, means permanently connected to another of said splined shafts operable to actuate said tool slide when said shaft is operated, gearing intermediate said vertical splined shaft and said cross rail shafts selectively engageable to connect said splined shafts for forward or reverse rotation with respect to said vertical shaft, gearing on said column-mounted tool support driven by said vertical splined shaft and selectively engageable to raise or lower said tool support, and means for actuating said vertical splined shaft at feed and traverse rates.

19. A planer having, in combination, a bed, a table slidable thereon, columns uprising on opposite sides of said bed, a cross rail slidable mounted on said columns, tool supports on said columns and cross rail, tool slides on said supports, feed screws extending vertically in said columns and operable to raise and lower said cross rail, means for actuating said feed screws simultaneously including a hollow shaft extending intermediate the lower ends thereof and through said bed, vertical splined shafts adjacent the columns for actuating the tool supports thereon and their slides, means for driving said splined shafts including a horizontal shaft extending between the lower ends thereof and through said hollow shaft, a gear loose on said horizontal shaft, means for clutching said gear to said horizontal shaft or to said hollow shaft, means for driving said gear at a traverse rate, means for actuating said horizontal shaft at a feed rate including a feed clutch, spring means urging said feed clutch toward engaged position, a crank and link device for shifting said gear, a first solenoid operable to actuate said crank to shift said gear into clutching engagement with said hollow shaft, a second solenoid operable to actuate said crank to shift said gear into engagement with said hori-

zontal shaft, and means operable by said crank to disengage said feed clutch except when said gear is in a neutral position.

20. A planer having, in combination, a bed, a table slidable thereon, a column uprising on one side of said bed, a cross rail slidably mounted on said column, tool supports on said column and cross rail, tool slides on said supports, a feed screw extending vertically in said column and operable to raise and lower said cross rail, means for actuating said feed screw including a hollow shaft, a vertical splined shaft adjacent the column for actuating the tool supports and their slides, means for driving said splined shaft including a shaft extending through said hollow shaft, a gear loose on said shaft, means for clutching said gear to said shaft or to said hollow shaft when the gear is shifted, means for driving said gear at a traverse rate, means for actuating said shaft at a feed rate including a feed clutch, means urging said feed clutch toward engaged position, a crank and link device for shifting said gear, a first solenoid operable to actuate said crank to shift said gear into clutching engagement with said hollow shaft, a second solenoid operable to actuate said crank to shift said gear into engagement with said shaft, and means operable by said crank to disengage said feed clutch except when said gear is in a neutral position.

21. A planer having, in combination, a bed, a table slidable thereon, a column uprising on one side of said bed, a cross rail slidably mounted on said column, tool supports on said column and cross rail, a feed screw extending vertically in said column and operable to raise and lower said cross rail, means for actuating said feed screw including a hollow shaft, a vertical splined shaft adjacent the column for actuating the tool supports, means for driving said splined shaft including a shaft extending through said hollow shaft, a gear loose on said shaft, means for clutching said gear to said shaft or to said hollow shaft when the gear is shifted, means for driving said gear at a traverse rate, means for actuating said shaft at a feed rate including a feed clutch, means urging said feed clutch toward engaged position, a crank and link device for shifting said gear, a first power-operated device operable to actuate said crank to shift said gear into clutching engagement with said hollow shaft, a second power operated device operable to actuate said crank to shift said gear into engagement with said shaft, and means operable by said crank to disengage said feed clutch except when said gear is in a neutral position.

PAUL S. JACKSON.
